[57] **CLAIM**

The ornamental design for a biopsy guide tube, as shown and described.

DESCRIPTION

FIG. 1 is a left side elevational view of a biopsy guide tube showing our new design;

FIG. 2 is a right side elevational view thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of FIGS. 1–6 is for illustrative purposes only and forms no part of the claimed design.
